UNITED STATES PATENT OFFICE.

LUCY V. HANSON, OF LEESBURG, FLORIDA.

GARMENT HANGER.

1,406,007.

Specification of Letters Patent.

Patented Feb. 7, 1922.

Application filed September 18, 1919. Serial No. 324,974.

To all whom it may concern:

Be it known that I, LUCY V. HANSON, a citizen of the United States, residing at Leesburg, in the county of Lake and State of Florida, have invented certain new and useful Improvements in Garment Hangers, of which the following is a specification.

This invention relates to garment hangers, and an object of the invention is to provide 10 a garment hanger of artistic appearance which embodies a pair of pivoted jaws, held in article or garment gripping position as by spiral spring and supported by a suitable suspending hanger or hook straddling the 15 finger gripping portions of the jaws, which is constructed of wire and has its ends in-turned and extending into the coils of the springs, and which may also form pivots for pivotally connecting the garment jaws of the 20 hanger.

Other objects of the invention will appear in the following detailed description taken in connection with the accompanying drawing forming a part of this specification, and 25 in which drawing:

Figure 1 is a side elevation of the improved garment hanger.

Figure 2 is an edge elevation of the garment hanger.

30 Figure 3 is a bottom plan of the hanger.

Figure 4 is a side elevation of a modified form of the handle structure, and

Figure 5 is a detail perspective view of a modified form of the garment hanger.

35 Referring more particularly to the drawings, the garment hanger comprises a pair of garment gripping jaws 10 and 11, which are preferably constructed of sheet metal, enameled in any desired color or nickel plated

40 to add to the attractiveness of the appearance of the hanger. These jaws 10 and 11 are shaped to form parallel laterally extending portions 12, projecting upon each side of the lower edge of the intermediate portions 13

45 of the jaws. As clearly shown in Figure 2 of the drawings the intermediate portions 13 angle outwardly from each other and are relatively wide, thus forming upstanding finger grips to permit the spreading of the lower engaging edges of the plate, to release

50 the garment from the hanger structure. The jaws 10 and 11 have their intermediate portions, at their lower edges, bulged outwardly as shown at 14 along the garment gripping portions thereof to accommodate the thickened portions of a garment at the seams,

and to insure a firm grip upon the garment by the hanger. The jaws 10 and 11 have ears 15 struck therefrom and the ears upon one end of each of the handle or intermediate portions 13 overlap, as shown in Figure 2 of the drawings, and are perforated, to receive therethrough the inturned ends 16 of the handle or hanging handle 17. This handle 17 is preferably made of a single strand 65 of wire bent intermediate its ends and having the lengths adjacent the bent portion twisted together, and shaped to form a hook 18, adapted to engage over a nail, clothes hook, or analogous support, while the lengths of 70 wire are spread to form a depending U-shaped portion straddling the finger-grip or intermediate portions 13 of the jaws 10 and 11 thus straddling said handgrip. The lower inturned ends 16 of the handle or hanger 75 extend through the perforations in the ears 15, pivotally connecting the plates 10 and 11, and they also extend into the convolutions of the spiral spring 19 and serve as a support therefor. One end of the spring 19 80 engages the jaw 10, while the other end engages the jaw 11, as clearly shown in Figure 2 of the drawings, the said spring being adapted to hold the lower garment gripping portions or edges of the jaw together, to 85 form a secure grip upon a garment.

In Figure 4 of the drawings, a modified form of the handle structure is shown, this form comprising an inverted U-shaped portion 20, which is constructed of a single 90 length of wire, twisted intermediate its ends to form an eye 21, and extending in opposite directions from the eye to straddle the hand grip portions or intermediate portions of the jaws of the garment hanger, and having 95 its terminals inturned as shown at 22, to form the pivot pin for the jaws, and also to form reinforcements and supports for the spiral spring which holds the jaws together. A hook 23 is connected, by means of an eye 100 24, formed thereon, to the eye 21, the said eyes 21 and 24 forming a pivotal connection between the hook 23 and portion 20, permitting the handle structure to be folded, when it is desired to pack or store the 105 garment hanger.

In Figure 5 of the drawings, a further modification of the garment hanger is shown, and this modification comprises a pair of relatively narrow engaging jaws 30, 110 and 31, which are pivotally connected by means of a spring 32, the coils of the spring

acting as a fulcrum for the pivotal movement of the jaws 30 and 31, while the ends of the spring are bent to engage across the jaws outwardly of their pivots or fulcrum 5 as shown at 33, to hold the lower garment gripping edges of the jaws in engagement with each other, or in gripping engagement with a garment. The handle 34 of this modified form of the garment hanger is 10 preferably formed of a single length of wire, bent intermediate its ends and having the portions adjacent the bend therein twisted and shaped to form a hook as shown at 35, while the sections of the lengths of the wire 15 at the lower terminal of the twisted portions are spread to constitute an inverted U-shaped portion to straddle the upper or hand grip portions of the jaws 30 and 31. The terminals of the handle 34 are inturned 20 as shown at 36 and extend into the convolutions of the spring 32, to connect the handle 34 to the jaws 30 and 31.

Changes in details may be made without departing from the spirit of this invention, but;

I claim:

1. In a garment hanger, the combination of a pair of jaws having upstanding finger grip extensions movable toward each other 30 to open the jaws, means yieldably urging said jaws toward each other, and a hanging

handle comprising a hook and a depending inverted U-shaped portion straddling said finger grip extensions and pivotally connected to said jaws substantially intermediate their ends whereby said finger grip extensions may be swung through said inverted U-shaped portion to facilitate manipulation of the jaws while the hanger is being supported from said hanging handle.

2. In a garment hanger, the combination of a pair of jaws having upstanding finger grip extensions movable toward each other to open the jaws, means yieldably urging said jaws toward each other, and a hanging handle comprising a hook and a depending inverted U-shaped portion straddling said finger grip extensions and pivotally connected to said jaws intermediate the ends of the jaws and finger gripping extensions, whereby said finger grip extensions may be disposed with the medial plane between said jaws and finger grip extensions coincident with the plane of said U-shaped portion, or swung to pass through said plane to permit the jaws to assume a pendant position responsive to the force of gravity when the handle is at an angle to the vertical, said hook being in the plane of said U-shaped portion.

LUCY V. HANSON.
